UNITED STATES PATENT OFFICE.

EDWARD N. SMART, OF MADISON, NEBRASKA.

SURGICAL APPLIANCE.

1,313,344.

Specification of Letters Patent.

Patented Aug. 19, 1919.

Application filed August 22, 1917. Serial No. 187,582.

To all whom it may concern:

Be it known that I, EDWARD N. SMART, a citizen of the United States, residing at Madison, in the county of Madison and 5 State of Nebraska, have invented certain new and useful Improvements in Surgical Appliances, of which the following is a specification.

My invention relates to a new and useful 10 improvement in surgical appliances, and refers particularly to a metal surgical splint for use on fractured limbs.

The primary object of this invention is the provision of a surgical splint made of metal, 15 which is pliable and capable of adjustment to fit any limb and to suit the particular kind of fracture it may be required for.

A further object of my invention is the production of a splint of the character 20 stated, which will in no manner rub or chafe the skin and which will be of extremely simple construction, thereby producing an appliance of this character which will be inexpensive to manufacture.

25 With the above and other objects in view which will appear as the description proceeds the invention consists in the novel construction, combination and arrangement of parts, hereinafter described and claimed, it 30 being understood that changes in the precise embodiment of the invention herein disclosed can be made without departing from the spirit of the invention.

In the accompanying drawings, I have 35 illustrated one complete example of the physical embodiment of my invention constructed according to the best mode I have so far devised for the practical application of the principles of the invention.

40 Figure 1 represents a side view of the lower limb illustrating my invention used in case of a fracture of the bone of the fore part of the leg.

Fig. 2 represents a side view of the fore- 45 arm with my splint used thereon, the usual bandages and cast being omitted in order that my invention may be more clearly shown.

Fig. 3 represents a top plan view of the 50 invention.

Fig. 4 represents a top plan view of my invention, in which view six supporting wires are used.

Fig. 5 represents a transverse sectional 55 view taken on line 5—5 of Fig. 3, and

Fig. 6 represents a view taken on line 6—6 of Fig. 3.

My invention entirely replaces the old fashion wooden splints as it can be flexed or bent to conform to the shape of any limb or 60 portion of the limb, but still is sufficiently strong and stiff to retain the form into which it is bent to properly support the fractured bone.

The invention is simplicity itself and consists of the pliable plates 10, preferably of 65 soft copper or the like having the raised or struck up portions 11 through which pass the longitudinal retaining or supporting wires 12 which are also pliable and of soft 70 copper or the like.

One of these plates 10, as indicated at 10' is used as the end plate and the ends 13 of the wires 12 are bent around or curved and engage the openings or passages 14 under the struck up portions 11, through which the next adjacent wire passes, as shown in Fig. 3.

As many of the plates 10 may be used as required, and also as many wires 12 may be 80 used, the plates 10 of course being provided with sufficient openings 14 to accommodate the wires. See Fig. 1 in which four (4) plates 10 are utilized, and in Fig. 2, only 85 three (3) of these plates are used.

As will be at once apparent to those skilled in the art to which an invention of this character appertains, my splint is used in practically the same manner as the old wooden splint; however, the plates 10 and the wires 90 12 are adapted to be bent to conform to the shape of the limb or to suit the fracture being treated and then wrapped with bandages as is usually the case.

I claim:

1. A surgical splint comprising two flat plates spaced from each other, a series of substantially parallel and spaced wires having their opposite ends connected to said plates respectively, one or more other plates 100 arranged transversely of said wires and connected thereto between said first plates, said plates and wires being of pliable material having sufficient rigidity to retain their applied shapes under normal conditions, 105 whereby the splint may be shaped to required forms.

2. A surgical splint comprising two flat plates spaced apart and having a plurality of spaced loops struck from said plates, a 110

series of spaced and parallel wires each having its opposite ends extending through a corresponding loop in said plates, respectively, and having its extremities bent to project in the loop of an adjacent wire, and an intermediate plate having loops struck therefrom through which said wires pass.

In testimony whereof I affix my signature in the presence of two witnesses.

EDWARD N. SMART.

Witnesses:
